UNITED STATES PATENT OFFICE

2,547,383

BUBBLE CAP RISER

Hans C. Glitsch, Dallas, Tex., assignor to Glitsch
Engineering Company, Dallas, Tex., a partnership

Application September 29, 1947, Serial No. 776,737

4 Claims. (Cl. 261—114)

1

This invention relates to new and useful improvements in bubble cap risers for use in refining vessels.

One object of the invention is to provide an improved riser for a bubble cap adapted to be supported and secured in position by coaction with the bubble cap.

Another object of the invention is to provide an improved bubble cap riser having means at its upper portion for securing a bubble cap thereto without materially decreasing the flow capacity of the riser.

An important object of the invention is to provide an improved riser, of the character described, having upright supports at its upper end for receiving a cap engaging bar, the supports projecting above the open upper end of the riser whereby the flow capacity thereof is substantially unrestricted.

A particular object of the invention is to provide an improved riser, of the character described, wherein the upright supports are made integral with the riser so as to be formed of normally waste material and eliminate the necessity of attaching the same to said riser.

A further object of the invention is to provide an improved riser, of the character described, which is of such simple construction as to be manufactured economically from a minimum period of time.

A construction designed to carry out the invention will be hereinafter described together with other features of the invention.

The invention will be more readily understood from a reading of the following specification and by reference to the accompanying drawing, wherein an example of the invention is shown, and wherein:

Fig. 1 is a transverse, vertical, sectional view of a riser constructed in accordance with the invention and shown mounted with a bubble cap in a riser opening.

Fig. 2 is a top plan, partly in section, of the mounted bubble cap and riser.

Fig. 3 is a perspective view of the wedge member for locking the riser to the cap.

Fig. 4 is a detailed, sectional view, showing the connection between one of the riser arms and the cross bar.

Fig. 5 is a transverse, vertical, sectional view of the riser prior to assembly of the cross bar, and

Fig. 6 is a transverse, vertical, sectional view of the lower portion of a slightly modified construction.

2

In the drawing, the numeral 10 designates a bubble cap assembly which includes a riser 11 and a bubble cap 12 mounted upon a tray floor or deck 13 of a refining vessel (not shown) above a riser opening 14. The bubble cap 12, which rests upon the deck 13, is of conventional construction and has a plurality of slots 15 in its depending skirt portion. An elongated opening or slot 16 is formed in the top of the cap for coacting with the riser 11, as will be hereinafter more fully explained. The riser includes a short tubular body or collar 17 and has its lower end swaged or flared outwardly to provide an external, peripheral flange or lip 18 for engaging beneath the edge portion of the deck surrounding the riser opening 14.

As shown in Fig. 6, a tray floor or deck 19 of relatively-thin metal may be used in place of the deck 13 and has flanged openings 20 therein for receiving the lower ends of the risers. The marginal edge portion of the deck 19 surrounding each opening 20 is swaged or belled upwardly so as to coact with the peripheral flange 18 of the riser.

The riser body 17 is formed from a flat sheet of relatively-thin metal which is preferably extruded to cup shape. Upon removing the bottom of the cup, a pair of diametrically-opposed blanks or projections 21 are left so as to provide substantially upright supports or short arms which bend outwardly at right angles. It is desirable to remove the flat portion of the cup bottom only, whereby the curved or arced margin 22 thereof remains (Figs. 4 and 5). The arms 21 project from the inner peripheral edge portion of the margin 22 so as to be disposed inwardly of the external diameter of the body in substantially parallel relation. An elongated opening or slot 23 is formed in each arm and extends longitudinally thereof. If desired, the upper end of each arm may be rounded or bevelled as shown by the numeral 24. The peripheral flange 18 may be formed upon extrusion of the cup or subsequently thereto.

A transverse member or cross bar 25 is adapted to be supported by the riser arms 21 and is of a flat, substantially rectangular shape. Each end of the cross bar 25 is of reduced width to provide a short projection or tongue 26 for engaging within the slot 23 of one of the arms. Manifestly, the cross bar is of a length substantially equal to the distance between the arms. A lateral connecting element or leg 27 extends at a right angle from the medial portion of one longitudinal edge of the cross bar and is adapted to project

above the arms when the tongues 26 are properly engaged within the arm slots 23. The leg 27 extends through the opening 16 of the bubble cap 12 when the latter is positioned over the riser and has a longitudinal slot or opening 28 therein for receiving a locking element 29 which overlies and bears against the top of said bubble cap. To facilitate insertion of the leg 27 in the opening 16, the extremity 30 of said ear is preferably rounded or bevelled.

As is most clearly shown in Fig. 3, the locking element 29 is preferably in the shape of an elongated, tapered wedge and may be formed of two bars 31 and 32, of relatively thin metal, spot-welded or otherwise secured together. When made in two pieces, the small ends of the bars may be spread to prevent accidental displacement of the element 29. A notch or recess 33 is formed in each longitudinal edge portion of the locking element adjacent its large end to facilitate removal thereof by a suitable tool (not shown). With the riser 11 extending upwardly through the opening 14 of the deck 13, or the opening 20 of the deck 19, and with the cross bar 25 in place, the connection of the cap 12 to the leg 27 by the locking element fastens said riser within its opening. Due to the wedge action of the locking element, the peripheral flange 18 at the lower end of the riser is drawn upwardly into fluid-tight sealing engagement with the marginal edge portion of the deck surrounding the riser opening.

In order to facilitate insertion of the tongues 26 of the cross bar 25 in the slots 23 of the riser arms 21, the extremities of said tongues are rounded or bevelled and particularly at the lower portions thereof as shown by the numeral 34 (Fig. 4). The tongues are formed by notching or cutting away the upper corners of the cross bar as shown at 35, whereby said tongues are positioned at the lower end portions of said cross bar. By relieving the upright wall or margin 36 of each notch 35 so that the same extends upwardly and outwardly at an inclination, one tongue may be engaged within its respective slot while the other tongue is disposed below the slot of the other riser arm. In this position, the cross bar is inclined and the inclined wall 36 of the notch bears against the inner surface of the riser arm. Due to the bevel 34 of the unengaged tongue extremity, the cross bar may be pushed or forced upward readily so as to move the unengaged tongue into engagement with its slot. Upon such engagement, the extremities of the tongues are punched with a die or other tool (not shown) so as to swage or stake said tongues into engagement with the slots of the riser arms as shown by the numeral 37.

From the foregoing, it is believed to be readily apparent that an efficient riser of simple inexpensive construction has been provided. Since the riser arms are formed from normally waste metal, the same are obtained at practically no cost and a saving is effected by eliminating the necessity of attaching separate arms to the riser. In addition, the riser may be readily assembled in a minimum period of time to further increase the economy of manufacture. As has been pointed out, the capacity or flow area of the riser is not materially decreased due to the positioning of the cross bar above the upper end of said riser.

The inward disposition of the arms relative to the body of the riser not only facilitates insertion of the riser in a deck opening but also eliminates the necessity of rebending said arms along a previous bend.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A riser for a bubble cap including, an upright tubular body, a pair of diametrically opposed arms made integral with and projecting above the upper end of the body, each arm having an elongated vertical opening therein, and a flat cross bar disposed in a vertical plane between the arms wholly above the upper end of said body and having its ends engaging within the openings thereof, said ends being distorted to prevent displacement of the cross bar, the cross bar having means intermediate its ends for connection with a bubble cap.
2. A riser as set forth in claim 1 wherein the end portions of the cross bar are reduced and rounded to facilitate engagement thereof within the openings of the riser arms.
3. In a bubble cap riser having substantially upright slotted supporting arms projecting above its upper end in opposed relation, a cross bar for connection with a bubble cap disposed between the riser arms wholly above the upper end of the riser, and tongues of reduced width carried by the ends of the cross bar for engaging within the slots of said riser arms, the ends of the tongues having bevelled portions at one side, the ends of said cross bar opposite the bevelled portions of said tongues being relieved to cooperate with the bevelled ends of said tongues to facilitate insertion thereof in the arm slots.

4. A bubble cap riser including, an upright tubular body, a pair of opposed arms integral with and projecting above the upper end of the body, the arms being offset inwardly of said body and having vertical openings in their offset upper end portions, and a flat cross bar for connection with a bubble cap having reduced ends projecting through and secured in the openings, the cross bar extending in a vertical plane above the upper end of said body.

HANS C. GLITSCH.
